UNITED STATES PATENT OFFICE.

WILLIAM H. McDONOUGH, OF NEW YORK, N. Y., ASSIGNOR, BY MESNE ASSIGNMENTS,
TO THE AMERICAN BRAKE SHOE AND FOUNDRY COMPANY, OF WILMINGTON, DELA-
WARE, A CORPORATION OF DELAWARE.

BRAKE-SHOE.

1,228,683.

Specification of Letters Patent.

Patented June 5, 1917.

Application filed April 25, 1916. Serial No. 93,363.

To all whom it may concern:

Be it known that I, WILLIAM H. McDONOUGH, a citizen of the United States, residing at New York, in the county and State of 5 New York, have made a certain new and useful Invention in Brake-Shoes, of which the following is a specification.

This invention relates to brake shoes.

The object of the invention is to provide a 10 brake shoe which is strong and durable, and which is economical to manufacture.

Further objects of the invention will appear more fully hereinafter.

The invention consists substantially in the 15 construction, location, combination and relative arrangement of parts, all as will be more fully hereinafter set forth, as shown in the accompanying drawing, and finally pointed out in the appended claims.

20 Referring to the drawing:—

Figure 1 is a plan view of a brake backing plate embodying my invention.

Fig. 2 is a broken sectional view of the same, taken on the line 4, 4, Fig. 1, and looking 25 in the direction of the arrows.

Fig. 3 is a broken view in plan showing a modified form of lug and embodying my invention.

Fig. 4 is a sectional view of the same taken 30 on the line 6, 6, Fig. 3, and looking in the direction of the arrows.

Fig. 5 is a plan view of a still further modified form of lug employed in accordance with my invention.

35 The same part is designated by the same reference numeral wherever it occurs throughout the several views.

It is the common practice in the manufacture of brake shoes to employ a reinforcing 40 sheet of steel or other ductile metal to the back of a shoe body and to secure the two together in a convenient manner, the metal reinforcing sheet being provided or formed with a key lug to secure the shoe to the brake

45 head. It is a common expedient to produce the key lug by slitting the sheet metal back and punching or pressing out the slit portions. The obvious objection to this method

is that the greatest strain upon the sheet 50 metal back is at the point of the lug thereon. Therefore, when the lug is formed by slitting or cutting away the metal back at that point, the metal back is considerably weakened. It is also a common expedient to

bend, crimp or twist the sheet metal back to 55 form the key lug. The same objection hereinbefore noted applies equally well to this arrangement as it is obvious that bending or crimping or twisting the sheet metal back greatly decreases the strength thereof at 60 the point where the lug is formed, which, as hereinbefore stated, is the point of greatest strain upon the backing.

It is also a common expedient to make lugs separate from the backing, and to secure 65 the lug and backing to each other by the cast metal forming the shoe. It is obvious that this arrangement necessitates a cast metal reinforcement for the lug, which is objectionable because the cast metal is not 70 sufficiently strong for this purpose.

It is among the special purposes of my invention to overcome the objections above noted, and to provide a shoe structure in which the shoe body is cast onto a sheet 75 metal backing plate, the latter being perforated or formed with openings in the usual manner. I also propose to provide key lugs separate from the backing plate and to efficiently secure the key lugs to the 80 backing plate in any well known manner, such as by welding it thereto, thereby eliminating twisting, crimping or binding the backing plate to form the lug, or cutting or slitting the backing plate and thereby weak- 85 ening it.

In the drawing 10 designates the sheet metal reinforcing plate or backing to be applied to the shoe body. The plate 10 is 90 perforated or provided with openings therethrough, as indicated at 12, and is usually curved to conform to the shape of the shoe body, and is placed in the mold into which the metal to form the shoe body is poured, whereby such metal, when poured, not only 95 forms the shoe body, but also flushes through the openings or perforations 12 of the backing or reinforcing plate, thereby efficiently attaching the plate and the shoe body together. It is obvious that the openings or 100 perforations 12 may be of any desired number, size or shape.

As above explained, I provide a key lug 105 designated at 13, which I secure to the backing plate by welding it thereto. The key lug may be formed in any desired manner.

In Figs. 1 and 2, I show a form of lug, wherein the lips 15 are outwardly flanged to

rest upon the backing plate 10, as shown, and are then welded thereto.

It is desirable to have the outer surface of the lug lips flush with the outer surface of the backing, and in Figs. 3 and 4, I show an arrangement wherein this feature is accomplished. In this arrangement I provide each side of the lug 13, with two comparatively narrow lips 16 and 17, which lips seat in depressions hammered or pressed in the backing 10, as shown. The lips 16 and 17, are welded to the backing as hereinbefore described. In this arrangement it will be seen that at the point of the lug on the backing, the backing is materially reinforced by the separate lug due to the full thickness of the backing plate between the lug sides and at the same time obviating the necessity of building up on the end of the brake head 20 which would be necessary if the lug lips were not flush with the surface of the backing plate.

In Fig. 5 I show a modified form of lug lip 18 which is welded to the backing plate, and which may be either seated in a depression in the backing plate and welded thereto, or seated on the surface of the backing plate and welded thereto as shown in Fig. 2.

I have found that by the arrangements of lugs and the reinforcing backing plates

herein described, it is possible to greatly strengthen the brake shoes, and the cost of maintenance is considerably diminished.

While I have shown and described specific structures embodying my invention, I wish it to be understood that many other forms and arrangements will readily occur to those skilled in the art without departing from the broad scope of my invention. Therefore, what I claim as new and useful, and of my own invention and desire to secure by Letters Patent, is—

1. In a brake shoe, a sheet metal reinforcing back and a key lug provided with outwardly flanged lips, said lips being welded to said back. 45

2. In a brake shoe, a sheet metal reinforcing back provided with depressed portions, a key lug provided with outwardly flanged lips to seat in said depressed portions, said lips being welded to said back. 50

3. In a brake shoe, a reinforcing back provided with depressed portions, a key lug having keyway openings in the sides thereof and provided with outwardly flanged lips, said lips seating within the depressed portions of the said back and anchored thereto. 55

In testimony whereof I have hereunto set my hand on this 22nd day of March, A. D. 60 1916.

WILLIAM H. McDONOUGH.
